DALPHIN L. HITTLE, OF ANDERSON, INDIANA, ASSIGNOR TO DELCO-REMY CORPORATION, OF ANDERSON, INDIANA, A CORPORATION OF DELAWARE

IGNITION DEVICE

Application filed May 16, 1930. Serial No. 453,096.

This invention relates to improvements in ignition devices for internal combustion engines.

It is among the objects of the present invention to provide an ignition device for an internal combustion engine, so constructed and arranged as to reduce to a substantial minimum, friction between moving parts.

Another object of the invention is to provide an ignition device with a circuit interrupter supporting base having ball bearings engaging both sides thereof whereby friction is substantially reduced when the base is operated to vary the angular relation between the circuit interrupter and its operating member to vary the time of sparking impulses for the engine.

A further object of the present invention is to provide an ignition device with means which substantially eliminate rattling between the moving parts thereof.

Further objects and advantages of the present invention will be apparent from the following description, reference being had to the accompanying drawings wherein a preferred embodiment of one form of the present invention is clearly shown.

In the drawings:

Fig. 1 is a plan view of the ignition device with the distributor cap removed in order more clearly to show the circuit interrupter mechanism.

Fig. 2 is a sectional view taken along the line 2-2 of Fig. 1.

Fig. 3 is a fragmentary detail sectional view taken substantially along the line 3-3 of Fig. 1.

Fig. 4 is a transverse section taken along the line 4-4 of Fig. 2.

Fig. 5 is a view similar to Fig. 4, taken along the line 5-5 of Fig. 2.

Fig. 6 is a detail fragmentary view taken along the line 6-6 of Fig. 1.

Referring to the drawings, and more particularly to the Figs. 1 and 2, the ignition device is shown comprising a cup-shaped housing 20 having an annular wall 21. A tubular extension 22 on the housing provides a means whereby the distributor may be attached to any suitable part of the engine, this

tubular portion 22 also forming a journal in which the drive shaft 23 of the device is rotatably supported.

Within the housing 20 and attached to the drive shaft 23 is a plate 24, carrying posts 25 and 26 at diametrically opposite sides thereof. These posts pivotally support the centrifugal weight members 27 and 28 respectively. A tubular member 29 is rotatably supported on the smaller diameter portion 60 of the drive shaft 23, said tubular portion 29 having diametrically opposite arms 30 and 31 extending therefrom, which arms are engaged by extending lips 32 and 33 respectively of the weights 28 and 27 respectively.

On the arm 30 of the tubular member 29 a post 34 is provided and a similar post 35 is provided on the arm 31 of said member. A spring 37 is connected between posts 26 and 34 of the weight 28 and arm 30 respectively while the spring 38 is connected between posts 25 and 35 of the weight 27 and arm 31 respectively. These springs normally urge the weight members 27 and 28 into the position 75 shown in the Fig. 4.

The tubular member 29 provides a cam 39 having six lobes in this instance. At the top of the tubular member 29 there is supported the rotor 40, which has a radial contact arm 80 41 extending therefrom and a spring supported central contact button 42.

From the foregoing it may be seen that the drive shaft 23 may transmit rotative motion to the tubular member 29 through the 85 weights 27 and 28. These weights in turn transmit rotative motion to the arms 30 and 31 through their tongues 32 and 33 respectively, which arms in turn are secured to or form a part of the tubular member 29.

In response to increasing speeds, weights 27 and 28 will move outwardly, thus tongues 32 and 33 will move counterclockwise about their respective pivot posts 26 and 25 to urge 95 the arms 30 and 31 in a clockwise rotation in addition to the rotation of said arms by the shaft, thus the cam 39 will be rotated relatively to shaft 23 in the direction of rotation for the purpose of advancing the time of 100

sparking impulses, as will be described more detailedly later.

A distributor cap 45 of any suitable insulating material fits upon the housing 20 and is secured thereto by clips 46, which are hingedly anchored to the annular wall 21 of the housing 20 by hinge clips 47. The distributor cap 45 has a central terminal socket 48 adapted to receive the high tension wire leading from the secondary winding of the ignition coil used in connection with this ignition device. This socket 48 has a button 49 engaged by the spring pressed button 42 of the rotor. A plurality of terminals 50, arranged in a circular row about the central terminal socket 48, have post portions 51 extending interiorly of the head 45 and lying in juxtaposition to the circular path taken by the radial contact element 41 of the rotor 40. It will be seen that sparking impulses from the secondary winding of the coil directed to the socket 48 are transmitted through the buttons 49 and 42 respectively through radial contact element 41 to the proper terminal post 51 in recurrent sequence and in proper order.

In the housing 20 there is provided an annular shoulder 60 which supports a base 61, said base having a central opening 62. This base is stationary within the housing 20. A plate 63 has a central opening, the edge of which is spun over the form and annular flange 64 which rotatably fits into the central opening 62 of the base 61 and thus plate 63 may be said to be pivotally supported by the base 61. Base 61 has recesses 65 substantially equally spaced, in each of which there is provided a retainer 66 secured to the base by having tangs extending through openings in the base and turned over. These retainers each contain a ball bearing 67 in such a manner that one side of the ball bearing rides upon the base 61 while the other side of the ball bearing is engaged by the plate 63. Thus plate 63 is supported upon the base 61 by friction reducing bearings.

Screws 68 and 69 are provided on diametrically opposite sides of the annular wall 21 of the housing 20, each screw performing two functions. One of these functions is the attachment by said screws of the longitudinal clips 47 to the outside of the annular wall 21, each screw also securing a retainer 70 within the inside of the wall 21. Each retainer has a ball bearing 71 which is urged into engagement with the top surface of the plate 63 by said retainer, and thus said plate 63 is maintained in engagement with the ball bearings 67 interposed between plate 63 and base 61.

From the foregoing it may be seen that plate 63 is supported on both sides, top and bottom, upon ball bearings 71 and 67 respectively.

The plate 63 has two spaced angular ex-

tensions 75 and 76, clearly shown in the Figs. 1 and 6. A spring blade 77 has its ends secured respectively to the angular extensions 75 and 76 of the plate 63. A retainer 78 is secured to the spring blade 77, said retainer 78 containing a ball bearing 79 which is yieldably urged into engagement with the inner surface of the annular wall 21 of housing 20. The spring 77 thus urges the plate toward the one side of the housing and consequently if any play exists between the annular flange 64 of plate 63 and the opening 62 in the base 61, this pressure of the spring 77 laterally will substantially prevent rattling of the plate 63 due to such imperfect fit with the base. 75 80

A terminal bracket 80 is also supported by the angular extensions 75 and 76 of the plate 63, said terminal bracket providing a support for the terminal clip 81, one end of which is attached to the terminal bracket by the screw stud 82, the other end of which has a slot 83 which fits over the pivot post 92 of the interrupter lever 84, thus maintaining said interrupter lever in proper position upon its pivot post. Terminal clip 81 has a wire 85 connected thereto which leads from the terminal post 86 insulatingly supported by the annular wall 21 of the housing. A wire 87 leads from the terminal clip 81 to the condenser 88 as shown in the Fig. 1. 90 95

The interrupter of the ignition device is supported upon the rotatable adjustable plate 63. This interrupter comprises a bracket 90 having a stationary contact 91, this bracket being pivotally secured to the post 92 carried by the plate 63. A clamping screw 93 is adapted to secure bracket 90 in any suitable adjusted position upon the plate 63. An adjusting member 94, eccentrically supported by the plate 63, has a head portion extending into an elongated slot in the bracket 90 whereby, when said adjusting member 94 is operated after screw 93 is loosened, bracket 90 may be pivotally adjusted about its post 92. The pivot post 92 which, as has been mentioned, has the bracket 90 pivotally secured thereto, also pivotally supports the circuit breaker lever 84 which has a contact 95 for engagement with contact 91. Lever 84 also has a wearpiece 96 engaged by cam 39. A spring conductor 98 has its one end secured to the terminal bracket 80 by the screw stud 82, the other end is secured to the circuit interrupter lever 84 by the same rivet 99 which secures rubbing block 96 thereto. This conductor spring or blade urging the lever 84 counter-clockwise so that a rubbing block 96 is yieldably urged into engagement with the cam 39. 100 105 110 115 120 125

On the outside of housing 20 there is attached a bracket 100 which carries a pressure responsive element 101. As shown in the Fig. 3, this pressure responsive element 101 comprises two shell portions 102 and 103, secured together so as to form a chamber therebetween. This chamber is divided into two 130

compartments by a flexible diaphragm 104, the peripheral edge of which is clamped between the shell portions 102 and 103. At the central portion of the diaphragm 104 there is secured a connector button 105 which extends outside the shell portion 102. Within the chamber formed between the shell portion 103 and the diaphragm 104, a sleeve 106 is attached to the connector button 105. This sleeve member 106 is slidably supported within a tubular cylinder-like member 107 secured in an opening in the shell 103. A nipple 108 is attached to the cylinder part 107, this nipple being adapted to receive a pipe, not shown, but leading from any suitable suction chamber in the engine. A spring 109 is interposed between the nipple 108 and the sleeve member 106, this spring normally urging the diaphragm 104 toward the shell 102. The connections between shell 103 and the cylinder-like member 107 and nipple 108 are all substantially leak-proof. Connector button 105 has one end of lever 110 attached thereto, this lever extending through an opening 111 in the annular wall 21 of the housing and having its inner end 112 secured to the plate 63 in any suitable manner. Preferably this attachment of lever 110 to the plate 63 is adjacent its outer peripheral edge.

It will be understood that as the engine rotates the drive shaft 23, said drive shaft, as described heretofore, will rotate cam 39, and thus the lobes of cam 39 will recurrently push the rubbing block 96 to move the circuit interrupter lever 84 to disengage its contact 95 from the stationary contact 91 for the purpose of circuit interruption to provide sparking impulses.

When the speed of the engine increases, the weights 27 and 28 will, as has been described, transmit an additional rotation to the cam 39, and thus its lobes will earlier engage the rubbing block 96 on the circuit breaker lever in the cycle of the engine operation, thus advancing the time of sparking impulses.

The fluid pressure controlled device 101 operates in response to engine suction. When the suction of the engine increases, the diaphragm 104 is moved toward the shell 103 against the effect of spring 109, and consequently lever 110 is moved in the same direction. Lever 110 being connected with the plate 63, will rotate said plate 63 counter-clockwise as regards the Figs. 1 and 4, and thus the circuit interrupter lever 84 being supported on the plate 63 will also be moved counter-clockwise as the rubbing block 96 is moved in a direction opposite to the rotation of the cam 39, or more specifically as the rubbing block 96 is moved counter-clockwise, the time of contact between the wearpiece 96 and the cam lobes as regards the engine cycle of operation will be advanced and consequently the time of sparking impulses will be ad-

vanced in accordance with engine suction conditions.

Applicant in this invention has mounted the adjustable circuit interrupter supporting plate in such a manner that a substantial amount of friction is eliminated and thus the speed and suction controlled device may operate the plate more easily, consequently the adjustment device for the interrupter will be more sensitive to changes in engine conditions. The device is of sturdy construction, simple and compact, and its design is such as to enable it to be commercially produced at a minimum expense of time and labor.

While the form of embodiment of the present invention as herein disclosed, constitutes a preferred form, it is to be understood that other forms might be adopted, all coming within the scope of the claims which follow.

What is claimed is as follows:

1. An ignition device for an internal combustion engine comprising, in combination, a circuit interrupter; a member for operating said interrupter; a stationary base; retainers carried by the base, each containing a ball bearing; an adjustable plate seated upon said ball bearings and rotatably engaging the base, said plate supporting the circuit interrupter; and ball bearings engaging the plate and urging it upon the ball bearings carried by the base.

2. An ignition device for an internal combustion engine comprising, in combination, a circuit interrupter; a member for operating said interrupter; a stationary base; an adjustable plate; ball bearings interposed between the said plate and base; ball bearings engaging the plate to maintain it upon the aforesaid ball bearings; and means for rotatably adjusting the plate.

3. An ignition device for an internal combustion engine comprising, in combination, a housing; a base within said housing; a plate rotatably secured to said base; ball bearings interposed between the base and plate; ball bearings including retainers secured to the housing, said bearings engaging the plate to maintain it upon the aforementioned bearings; a ball bearing carried by the plate and engaging the housing laterally to support the plate; a circuit interrupter on said plate; means for operating said interrupter; and means for adjusting the plate to vary the angular relation between the interrupter and its operating member.

4. An ignition device for an internal combustion engine comprising, in combination, a housing having an annular wall; a base within said housing, having spaced recesses adjacent its outer edge; retainers secured to the base, one in each recess; a ball-bearing in each retainer; a plate having an annular flange rotatably engaging an opening in the base, said plate seating upon the ball bearings carried by said base; retainers carried by the hous-

ing; ball-bearings in said retainers, engaging the plate to maintain it upon the ball-bearing on the base; a retainer carried by the plate and having a ball-bearing which engages the 5 annular wall of the housing and laterally supports the plate; a circuit interrupter on the plate; a member for operating said interrupter; and means extending into the housing and engaging the plate for rotatably adjust- 10 ing the plate to vary the angular relation between the interrupter and its operating member.

5. An ignition device for an internal combustion engine comprising, in combination, 15 a cup-shaped housing having an annular wall; a stationary base within said housing, said base having a central aperture; a plate having an annular flange extending in said central aperture, pivotally supporting the 20 plate upon the base; ball bearings interposed between the plate and base; spaced angular projections on the plate; a spring blade secured at its ends to the respective projections of the plate; a retainer carried by the spring 25 blade; a ball-bearing in said retainer, urged into engagement with the annular wall of the housing by the spring blade, yieldably resisting lateral movement of the plate, substantially to prevent rattling thereof; a circuit 30 interrupter on said plate; means for operating said interrupter; and means extending into the housing and secured to the plate for rotating said plate to vary the angular relation between the interrupter and its operating member. 35

6. An ignition device for an internal combustion engine comprising, in combination, a housing; a distributor cap for said housing; clips hingedly attached to the housing for securing the distributor cap upon said housing; a stationary base within said housing; an interrupter supporting plate pivotally carried by the base; friction reducing bearings interposed between the plate and base; a plurality of retainers; means for securing a respective retainer and clip hinge to the housing; a ball bearing in each retainer, engaging the plate to maintain it upon the friction reducing bearings between said plate and base; and means extending into the housing and engaging the plate rotatably to adjust it. 50

7. An ignition device for an internal combustion engine comprising, in combination, a cup-shaped housing having an annular wall; 55 a stationary base within said housing; a plate pivotally supported by the base; friction reducing bearings between the plate and base; spaced, angular projections on said plate; a circuit interrupter carried by the plate, said 60 interrupter comprising a bracket supporting a contact and a lever pivotally supported on the plate and having a contact for engaging said other contact; a spring blade secured at its ends to the respective angular projections of the plate; a retainer secured to the spring 65

blade; a ball-bearing in said retainer, urged into engagement with the annular wall of the housing by the spring blade; a terminal bracket secured to one of the angular projections of the plate; a terminal clip attached to the terminal bracket, said terminal clip engaging the circuit breaker lever to maintain it upon its pivot; means for operating the circuit breaker lever; and means extending into the housing and connected with the plate for rotating it to adjust the circuit breaker lever relative to its operating member. 70 75
